UNITED STATES PATENT OFFICE.

JOHN GARDNER, OF CARNFORTH, ENGLAND, ASSIGNOR TO THE GENERAL ELECTRIC COMPANY LIMITED, OF LONDON, ENGLAND.

ELECTRIC SIGNALING APPARATUS FOR RAILWAYS AND THE LIKE.

Application filed August 18, 1920, Serial No. 404,371, and in Great Britain August 21, 1919.

This invention has reference to electric indicators for railways and the like, and it has for its object to provide an improved indicator to indicate the progress of railway 5 and like vehicles along a track or permanent way, and whether any section is or is not occupied by a train.

According to this invention, the indicator comprises two independent electromagnetic 10 coils or windings having a common armature or the like and each of which is adapted when energized to give rise to a magnetic field capable of attracting the single armature or the like when the other 15 coil or winding is partially or completely de-energized, in which attracted position the armature or the like remains until the influencing coil or winding is partially or completely de-energized.

Two arrangements of apparatus in accordance with the invention are illustrated in the accompanying drawings, whereof Fig. 1 represents one arrangement in which the electromagnetic receiving instrument 20 embodying a transversely movable part is shown in end view partly in section and the electrical circuits including the transmitter instruments and other parts are illustrated diagrammatically, Figs. 2 and 3 respectively 25 are side elevation and plan, partly in section, of the electromagnetic receiving instrument shown in Fig. 1. Fig. 4 is a view similar to Fig. 1 of an alternative arrangement wherein a movable part or armature moves 30 to and from the ends of the electromagnets. Figs. 5 and 6 respectively are sectional side elevation and plan of one form of transmitter instrument, and Fig. 7 is an end view of 35 part of the same.

Referring first to Figs. 1, 2 and 3, the receiving instrument therein illustrated comprises two electro-magnets a , a^1 , an arm, pointer or needle b , and a movable part or armature c which is connected with the latter or forms a part thereof and is adapted to be operated by either of the electro-magnets to move the pointer or needle b to either of the dotted positions shown in Fig. 1. The coils or windings of the electromagnets a , a^1 are attached to a single yoke member d in which is mounted or carried one adjustable end pivot e^1 of an arbor e , the other end pivot e^2 being ad-

justably mounted in a bracket f on a base f^1 of non-magnetic material to which the yoke member d is attached. The arbor e supports the armature or movable part c and is of greater diameter than is usual where a horseshoe magnet consisting of two coils or windings in series is employed, in order that it may serve as part of the magnetic circuit for the two independent magnets a , a^1 . By mounting the armature or movable part as described, it is adapted to move transversely to the axes of the cores of the electromagnets a , a^1 and a gap of more than usual dimensions can be provided between the poles of the magnets and such armature or movable part.

The pointer or needle b is adapted to 70 operate in conjunction with a dial inscribed as indicated in Fig. 1, with the customary characters, e. g. "Line clear" and "Train on line", and to either of these positions it is moved by the electromagnets a , a^1 when one of them is de-energized, or is energized to a greater extent than the other. The electromagnets are controlled by two transmitters g , g^1 which are so disposed relatively to a railway track as to be influenced by the 75 passage of a train thereover. Such influence has for effect to partially or completely de-energize either of the magnets by partially or wholly interrupting the circuits thereof and thus enables the movements of the 80 needle or pointer b to be effected automatically. The two transmitters g , g^1 are connected in normally closed circuits in series with the respective electromagnets a , a^1 , each of which is adapted, when energized, to give 85 rise to a magnetic field capable of attracting the single armature or movable part c from a position somewhat beyond a point midway between the two windings or magnets, while the armature is so suspended on the arbor e 90 as to move to a central position midway between the electromagnets when neither of the magnets is energized, thereby indicating through the pointer or needle b that the needle instrument is out of use or is not 95 working, such as, e. g., by the words "Line closed". The needle or pointer may be rigidly secured to the armature or movable part, or it may be otherwise connected therewith so as to follow the movements thereof, 100 or the armature may serve as the indicator. 105

The circuits of the electromagnets a, a^1 and the respective transmitters g, g^1 comprise a common source h of electric current, leads j, j^1 from the source h to the magnets a, a^1 respectively, leads k, k^1 from the magnets to the transmitters, and leads m, m^1 from the transmitters to the common source h .

The transmitters g, g^1 may be of any desired type adapted to permit or cause a cessation or diminution of electric current in a normally closed circuit. A preferred type of transmitter instrument is shown in Figs. 5, 6 and 7, and comprises two parallel and substantially thick brass or other suitable metallic strips, bars or reeds g^2, g^3 which are held at one end horizontally and gripped between two metal discs g^4, g^5 secured to the bottom of the casing g^6 . The reeds g^2, g^3 are insulated from each other and from the discs g^4, g^5 by mica or like insulating material which will freely transmit to the reeds any vibrations communicated to the casing. The reeds are so twisted or shaped that when viewed from their free ends as shown in Fig. 7, they resemble a broad letter V with the limbs downwardly inclined towards each other at an angle of about 90° and separated at their lower edges. Two flat carbon or other electrodes g^7, g^8 are so arranged on the upper inner faces of the reeds between the nodes and anti-nodes thereof as to form an open bottom V shaped gap, and on such electrodes is arranged parallel to the reeds a light and freely movable cylindrical carbon rod g^9 which is small enough to rest at the bottom of the gap between the electrodes g^7, g^8 without passing through the same, and is provided with enlarged ends to prevent longitudinal displacement from between the electrodes when in use, and serves as the only means of electrical communication between the electrodes g^7, g^8 . The leads k, k^1 and m, m^1 from the magnets a, a^1 and to the source h of electric current, respectively, are connected with the reeds g^2, g^3 of the transmitters g, g^1 at g^{10} and g^{11} , and the circuit is by way of one reed g^2 through the electrode g^7 thereon, then through the rod g^9 , the other electrode g^8 , and the reed g^3 on which the latter rests.

The reeds g^2, g^3 are of such a nature as to be affected by mechanical vibrations communicated to railway sleepers, to which the transmitters are secured, by the passage of a train over the rails, the vibrations passing from the sleepers to the reeds by way of the nodes thereof.

To enable each transmitter to be so adjusted as to be responsive to certain vibrations only, such as e. g. those of a train passing over a sleeper on which the instrument is placed, and not responsive to other like vibrations of less degree, such as e. g. those caused by a train passing over an adjacent track, there is included in the electrical cir-

cuit of each transmitter a variable resistance g^{12} as shown in Figs. 1 and 4 adapted to be adjusted for this purpose.

As an alternative to the carbon rod g^9 , there may be employed one or more balls 70 of conducting material.

In the circuits of the transmitters g, g^1 interrupting keys n, n^1 may be provided for manually interrupting the circuits to de-energize the magnets a, a^1 when desired, and there may also be provided in the circuits switches o, o^1 which can be closed across the terminals p, p^1 and q, q^1 to complete the circuits through the magnets a, a^1 and the transmitters g, g^1 or across the terminals p, p^2 and q, q^2 to short circuit or cut out the transmitters g, g^1 .

For convenience of understanding in the following description of the operation of the apparatus, the transmitter g which is arranged at the commencement of the section of track concerned and is acted upon by the train at the moment of entering the section, is referred to as the "entering transmitter", and the transmitter g^1 which is arranged at the end of the section and is acted upon by the train when leaving the section is referred to as the "leaving transmitter". Similarly, the corresponding magnets a, a^1 are referred to as the "entering magnet" and the "leaving magnet" respectively.

Normally, the switches o, o^1 will be closed across the terminals p, p^1 and q, q^1 , respectively, to complete the circuits through the magnets a, a^1 and their complementary transmitters g, g^1 . Both magnets a, a^1 will be energized to a like extent and exert a similar effect on the armature c and the latter and the pointer b will occupy the mid-position shown in full lines in Fig. 1. When a train enters the section of track concerned, the entering transmitter g will be influenced by the vibrations set up in the track, thus reducing or interrupting the current flowing through the entering magnet a and partially or completely de-energizing the latter. On the de-energizing of the entering magnet a , the leaving magnet a^1 attracts the armature c and the pointer b moves to the right as shown in dotted lines, and shows the indication "Train on line". Owing to the great gap between the armature c and the core of the entering magnet a , the armature continues to be attracted by the leaving magnet and the pointer b to indicate "Train on line" until the train reaches the leaving transmitter g^1 even though the entering transmitter may have previously become quiescent and the current flowing through, and the strength of, the entering magnet a been restored to the normal. When the train reaches the leaving transmitter g^1 this transmitter will be influenced by the vibrations set up by the train thus

- reducing or interrupting the current flowing through the leaving magnet a^1 and partially or completely deenergizing the same and releasing the armature c which is then attracted by the entering magnet a and moves the pointer b to the left as shown in dot-and-dash lines in Fig. 1, and gives the indication "Line clear" to show that the section of track concerned is no longer occupied 5 by a train. The armature c continues to be attracted by the entering magnet a and the pointer b to indicate "Line clear" until the entering magnet a is again partially or completely de-energized.
- 10 15 In the event of failure of the common source of electric current h both magnets a , a^1 will be de-energized with the result that the armature c and pointer b will assume the middle-position illustrated in full lines 20 and the indication "Line closed" or some equivalent indication will be given to show that the apparatus is out of order. It will be observed that once the armature and pointer have been operated by one of the 25 magnets a , a^1 they continue to move from one extreme signaling position to the other unless both magnets are de-energized by failure of the common source of electric current or otherwise.
- 30 35 The interrupting keys n , n^1 are preferably controlled by springs n^2 so that on the release of the keys after operation to interrupt the circuits of the corresponding magnets a , a^1 they automatically close the circuits of the magnets. Operation of the keys n in the circuit of the entering magnet a and transmitter g will by causing the corresponding signal or giving the corresponding indication give assurance as to the state 40 of the distant transmitter and of the line, which may in some cases have a length of several miles, while the operation of the key n^1 in the circuit of the leaving magnet a^1 and transmitter g^1 will enable the operator to restore the apparatus to its normal state, after a train has entered the section of track, without waiting until the train has reached the leaving transmitter. Simultaneous operation of the keys n , n^1 enables the 45 armature c and pointer b to move to the mid-position and the apparatus to be put out of use should this be required, and the apparatus may be retained out of use by retaining the keys n , n^1 in the operated position. The switches o , o^1 enable either or 50 both of the transmitters g , g^1 to be short circuited or cut out, in which case signals can only be given or an automatically given signal can only be cancelled by manual operation of the keys n , n^1 . Thus the invention provides, among other advantages, that the desired warning or signal shall be automatically caused by an approaching train while 55 permitting cancellation of such warning or signal either automatically by the train or manually by the operator, as e. g., by the gatekeeper at a level crossing.
- 60 65 In the arrangement of apparatus illustrated in Fig. 4, the magnets a , a^1 have separate portions r , r^1 for the magnetic circuits of the coils or windings so that the magnetic circuit of each magnet is separate from the circuit of other instead of the two magnetic circuits having a common return as in the previous arrangement. The movable part 70 or armature c is pivoted at s and comprises two parts c^1 , c^2 adapted to move to and from the ends of the poles of the magnets a , a^1 respectively. The armature c may be given a bias towards central position such as by gravity acting upon a weight c^3 depending from the armature below the pivot, and also if desired by a spring c^4 acting between the weight c^3 and the base f^1 so as to assume that position in the event of failure of the common source of current. The arrangement illustrated in Fig. 4 is applicable in cases where the angular movement of the armature is small and the magnets act as a 75 relay to control a local circuit containing a signaling device or indicator. The local circuit illustrated comprises a source of electric current t , a visual indicator u , a contact arm b^1 carried by the armature c , leads v and w connecting the source t with the arm b^1 and the indicator u respectively, and leads x and y through which the circuit is completed through the indicator u by the arm b^1 accordingly as the armature is attracted by the magnet a or the magnet a^1 80 to give the corresponding indication. 85 90 95 100 105 110 115 120 125 130
- In other respects, including its operation, the apparatus shown in Fig. 4 is the same as the apparatus illustrated in Fig. 1. It will be understood that although only two arrangements of apparatus in accordance with the invention have been described in detail, considerable variations may be made without departing from the nature of the invention.
- In most cases, the cut out switch o in the circuit of the entering magnet a and transmitter g may be dispensed with.
- What I claim as my invention and desire to secure by Letters Patent is:—
1. In a three position indicating device a pair of similar electro-magnets, a common current source to which said electromagnets are independently electrically connected, means in each of said connections for independently varying the strength of each magnet, an armature common to both electromagnets and biased to a position intermediate the electromagnets when both are deenergized, said armature being movable to one electromagnet and away from the other when the normal magnetic strength of said other electromagnet is reduced, the relation between the armature and the electromagnets being such that the armature is held by the

electromagnet to which it is moved after the strength of the other electromagnet is restored to normal and until the magnetic strength of the electromagnet to which it has been moved is reduced.

2. In a three position indicating device a pair of similar electro-magnets, a common current source to which said electromagnets are independently electrically connected, **10** means in each of said connections for independently varying the strength of each magnet, an armature common to both electromagnets and stationary in an intermediate position by the equalized pull of the electromagnets, said armature being movable to one electromagnet and away from the other when the normal magnetic strength of said other electromagnet is reduced, the relation between the armature and the electromagnets **15** being such that the armature is held by the electromagnet to which it is moved after the strength of the other electromagnet is restored to normal and until the magnet strength of the electromagnet to which it has been moved is reduced.

3. In a three position indicating device a pair of similar electro-magnets, a common current source to which said electromagnets are independently electrically connected, a **20** device in each of said connections capable, when subjected to vibrations, of varying the current passing to each magnet and therefore varying the strength of each magnet, an armature common to both electromagnets

and said armature being movable to one electromagnet and away from the other when the normal magnetic strength of said other electromagnet is reduced, the relation between the armature and the electromagnets being such that the armature is held by the **40** electromagnet to which it is moved after the strength of the other electromagnet is restored to normal and until the magnetic strength of the electromagnet to which it has been moved is reduced.

4. In a three position indicating device a pair of similar electro-magnets, a common current source to which said electromagnets are independently electrically connected, means in each of said connections for normally permitting the uniform passage of current but capable of varying the amount of current passing, an armature common to both electromagnets, said armature being movable to one electromagnet and away from the other when the normal magnetic strength of said other electromagnet is reduced, the relation between the armature and the electromagnets being such that the armature is held by the electromagnet to which it is **50** moved after the strength of the other electromagnet is restored to normal and until the magnetic strength of the electromagnet to which it has been moved is reduced.

In witness whereof I have hereunto set **55** my hand.

JOHN GARDNER.
